HIGHWAY GUARD FOR WET TRAFFIC LINES

Robert G. Corbin, Huntingdon, Pa., assignor to Wald Industries, Huntingdon, Pa., a corporation of Pennsylvania

Application April 3, 1956, Serial No. 575,891

6 Claims. (Cl. 116—63)

This invention relates to devices temporarily applied to wet traffic lines, such as painted centerline markings for highways, and more particularly it relates to guards for wet lines which are of such configuration that they will create the impression, in the mind of the motorist, that serious tire damage will result if they are run over, so that the motorist will tend to stay clear of the wet line and the guard will effectively perform its intended function.

As the guards, in accordance with the invention, may be made of such harmless materials like rubber or plastic or the like, there will be no actual damage even if a driving situation is such that a motorist is forced upon special occasion to contact the guard with the vehicle's tires.

Prior to the present invention, wet line guards have been made in forms which are symmetrical or substantially symmetrical and which will straddle a wet line. Such prior guards are adapted to be arranged over the wet line in more or less precise patterns and more or less considerable care is taken in their placement.

It is an object of the instant invention to provide a simple wet line guard which will effectively protect a wet traffic line.

It is another object of the instant invention to provide a simple and harmless wet line guard which creates the impression in the mind of the motorist that serious tire damage will result if they are run over, so that the motorist will tend to stay clear of the wet line.

It is still another object of the instant invention to provide a wet line guard of simple configuration from which projects harmless, but dangerous appearing projections.

It is a further object of the instant invention to provide a non-symmetrical appearing wet line guard with great versatility of placement so that it is effective in any one of a great many different potential positions.

Other objects and the nature and advantages of the instant invention will be apparent from the following description taken in conjunction with the accompanying drawings, wherein:

Fig. 1 is a plan view of a blank or preform from which a wet line guard in accordance with the invention may be made, the dotted lines representing fold lines to be used in forming the final guard from the blank;

Fig. 2 is a top plan view of the formed guard with the points D, F, A in a common horizontal plane corresponding to a road surface;

Fig. 3 is a view in perspective, looking at one end of the guard with the points D, F, and A resting on a horizontal plane;

Fig. 4 is a view of the formed guard, in perspective, in the position of having the points B, C, and E in a horizontal plane;

Fig. 5 is a view of the formed guard, in perspective, in the scale of Fig. 4, and while it appears to be similar to Fig. 2, actually the points D, E, and C are in a horizontal plane;

Fig. 6 is a view of the formed guard, in perspective,

2

in the position of having points D, C, and A in a horizontal plane;

Fig. 7 is a view of the formed guard, in perspective, in the position of having points D, F, and A in a horizontal plane;

Fig. 8 is a view of the formed guard, in perspective, in the position of having points F, A, and B in a horizontal plane;

Fig. 9 is a view of the formed guard, in perspective, in the position of having points E, F, and B in a horizontal plane; and

Fig. 10 is a reduced plan view of a modified form of blank with perforations formed therein.

Referring to Fig. 1 of the drawings, the rectangular planular blank of the guard to be subsequently formed from it comprises two short sides AB and DE and two long sides BD and AE.

The main body portion of the blank comprises the parallelogram ACDF. The dotted line CF is a fold line which divides the body portion into two body triangles ACF and CFD.

The main body portion ACDF is integrally connected at each short side with a pair of triangular wings ABC and FED. The dotted line AC is a fold line which divides the wing ABC from the body triangle ACF. The dotted line FD is a fold line which divides the body triangle CFD from the wing FED.

The guard as shown in Fig. 2, and also Figs. 3 to 9, inclusive, may be formed from the blank illustrated in Fig.

30 1. When the material of the blank shown in Fig. 1 is rubber or rubber-like material or thermosetting plastic, it may be in a partially cured state which may subsequently be changed to a fully cured state under the influence of heat and pressure while the blank is held between suitable forming dies corresponding to the shape of the finished guard illustrated in Fig. 2, for example. Thus, the guard may be manufactured from blank by the well known post-forming process heretofore utilized for post-forming partially cured thermosetting plastic planular sheets.

The guard shown in Fig. 2, for example, need not necessarily be formed from a planular blank as alternatively, for example, it may be injection molded from a granular raw material in a suitable die and the material used for the guard may be a suitable thermoplastic such as polyethylene for example.

45 After the guard is formed, as illustrated in Figs. 2 to 9, inclusive, the plane of the body triangle ACF will be approximately at right angles to the plane of the body triangle CFD and the plane of the wing ABC will be approximately at right angles to the plane of the body triangle ACF and the plane of the wing FED will be approximately at right angles to the body triangle CFD.

50 Thus, it will be understood that the finished guard will be an integral structure composed of a plurality of planular facets and projections, each of which has pointed or corner portions and each of which appears to be of different shape or size depending somewhat upon the angle from which the guard is viewed by the observer.

55 Figs. 2 to 9, inclusive, show some of the many positions which the guard may take upon the highway. The appearance of the guard to the observer, however, will be infinitely more varied than the variations of appearance in Figs. 2 to 9 would indicate, as by simply turning the guard as shown in any one of the views of Figs. 3 to 9, inclusive, in a constant horizontal plane and about a vertical axis, the appearance of the guard continuously changes.

60 The guard in accordance with the instant invention need not be placed in a precise and uniform pattern along a wet traffic line to be protected. The guards may not be precisely uniformly spaced though they may be so placed. Accordingly, it will be understood that the guard of this invention can be installed more rapidly along a wet line

as no special care need be taken with respect to uniform or symmetrical placement nor is such uniform placement desirable.

The non-uniform placement which may be effected economically and rapidly may contribute to the illusions which the guard itself creates in the mind of the motorist that the sharp-appearing angular projections must be respected and the result accomplished is that the wet line is best protected and in the most economical manner.

The guard, when fully formed, is nestable; that is, the guards prior to application to the highway may be nested for convenient storage in any suitable container or magazine from which they may be manually or automatically dispensed to association with a wet line on a highway for the purpose of protecting the line in the manner already described.

Though the guard illustrated in Figs. 2 to 9, inclusive, is formed of imperforate planes, the guard may be perforated to decrease the surface exposed to the wind. For example, the guard may be formed from the perforated blank illustrated in Fig. 10.

It will be obvious to those skilled in the art that various changes may be made without departing from the spirit of the invention and therefore the invention is not limited to what is shown in the drawings and described in the specification but only as indicated in the appended claims.

What is claimed is:

1. A highway guard for wet center lines and lane lines comprising a multi-plane body portion, said body portion comprising a first solid section and a second solid section, each of said sections having length, width and thickness, said first section having a main face disposed in a first plane in which said length and width occur, said second section having a main face disposed in a second plane

in which said length and width occur, said second plane being at angular variance with said first plane and said two main faces being contiguous, and a pair of wing elements, one of said wings being contiguous with the main face of said first section of said body portion, the second wing being contiguous with the main face of said second section of said body portion.

2. The structure recited in claim 1, said body portion comprising a pair of planular triangular sections.

10 3. The structure recited in claim 1, each of said wings being in the shape of a triangle.

4. The structure recited in claim 1, each of said wings lying in a plane arranged at an angle to the plane of the contiguous body portion.

15 5. The structure recited in claim 1, said body portion comprising two contiguous triangular sections.

6. The structure recited in claim 1, said body portion comprising two large triangular sections, and each of said wings comprising a relatively small triangular section,

20 20 whereby the appearance of the guard on the highway to the observer will be that of an integral structure composed of a plurality of planular facets and projections each of which has pointed or corner portions and each of which appears to be of different shape or size depending somewhat upon the angle from which the guard is viewed by the observer.
